RUDOLPH A. TRANSUE, OF BROOKLYN, NEW YORK, ASSIGNOR TO WESTINGHOUSE LAMP COMPANY, A CORPORATION OF PENNSYLVANIA

ADVERTISING DEVICE

Application filed August 22, 1930. Serial No. 477,001.

This invention relates to advertising devices and an object of the invention is to provide a useful article in combination with advertising matter in such relation to the article as to advantageously display the advertising matter when the article is put to the use for which it is intended.

It is well known that advertising is not merely the placarding of descriptive matter haphazardly but that considerable thought and consideration must be given to the locating and vantage points of the displayed matter.

In accordance with the present invention an article of general utility is employed as a mounting or vehicle to bring advertising matter to the attention of the public.

It having been observed that when a water can is used to supply water to the radiator of an automobile, that this operation is necessarily performed in conspicuous view of the occupants of the automobile who usually give this operation a certain amount of attention.

In carrying out the present invention advantage is taken of the construction of the water can by providing the same with suitably positioned advertising matter so that as the can is lifted to discharge its contents into a radiator of an automobile a placard or surface having the said advertising matter thereon may be presented to the view of the occupants of the automobile.

The inscription or printed matter may be so applied as not to interfere with the operation or handling of the can during use and when the can is not in use it is immaterial whether or not the advertising matter has an advantageous or conspicuous position since the primary object of the invention is to so locate the advertising matter with respect to the can so that merchandise to be advertised will, by reason of the manipulation of the can, be presented to view in a most conspicuous and forcible manner.

The invention will be more fully understood by reference to the following description together with the accompanying drawing in which,

Fig. 1 is a perspective view of a water can

with the spout in position over the water inlet of an automobile radiator and showing advertising matter applied to the can in accordance with the present invention;

Fig. 2 is a view taken on lines II—II in Fig. 1;

Fig. 3 is a plan view of a frame or holder for holding a card or placard;

Fig. 4 shows a removable plate attachable to the can and on which printed matter may be applied;

Fig. 5 is a view taken on lines V—V in Fig. 4.

In carrying out the present invention of providing an advertising device, a can 9 may be employed, such for example as is used to supply water to an inlet 10 of an automobile radiator 11.

The can 9 is provided with an upper handle 12 and a lower handle or grip 13. Projecting at an angle to the surface of the can is a spout 14 having an outlet nozzle 15. The open top 16 of the can may be provided with a partial closure or shield 16 which serves to prevent an overflow of water as the can 75 is tipped upwardly during use.

It has been observed that an advantageous position for advertising matter is on the said shield 16 either directly or by providing a removable frame or holder 17 as shown. This frame may be of thin sheet metal of substantially the same shape as the upper surface of the shield 16 so as to cover the same when in position thereon.

For the purpose of retaining the frame in place a plurality of bendable ears 18, 19 and 20 are provided. The ears 18 and 19 may be bent about the inner edge of the shield while the ears 20 may be bent to grip the edge or bead 21 around the can top. Bendable clips 22 are also provided to over-lap and secure in place a card 23 bearing suitable advertising matter. The frame 17 may thus be fixed to the shield and since the cards 23 are removable they may be replaced from time to time with others so that new advertising matter may be presented as desired.

Although the use of removable cards may be of considerable advantage it may be desirable to provide a plate having advertis-

ing matter printed directly thereon. For this purpose a plate 25 of metal or other suitable material may be provided. This plate may be of the same general shape as the outer surface of the shield 16 and may be formed with bendable members 26, 27 and 28.

The members 26 and 27 may be bent about the inner edge of the shield and the members 28 may be bent to grip the edge or bead of the can. Although it has been found preferable to provide a sheet metal frame or plate with integral ears or clips to secure the frame or plate in place it is to be understood that other suitable securing means may be employed.

Plates 25 as above described may be of stamped sheet metal and are comparatively low in cost so that a variety of such plates may be provided each having a different inscription to vary the advertisement statements and since the plates are readily removable they may be easily changed as desired.

The above described advertising device does not provide a printed statement on an article to be seen haphazardly but is directed to an advertising surface in combination with means for advantageously presenting such surface to an observer. The application of a legend or other descriptive matter to a water can for automobile radiators brings about a novel condition and co-relation of the advertising matter and the can converting the can by reason of its particular function into an effective and convenient device for advertising purposes.

It is to be understood that the selected embodiment of the invention shows a preferred form but that modifications may be made therein without departing from the scope and spirit of the invention as defined by the appended claims.

What is claimed is:

1. In combination with an automobile radiator water supply can having a spout and a shield to partially close the open top of said can and disposed adjacent to said spout, a plate to receive a placard, means for securing said placard to said plate and means for securing said plate on the upper surface of said shield to position the placard within the range of vision of the occupants of an automobile when the end of said spout is positioned to discharge water into the inlet of an automobile radiator.

2. In combination with an automobile radiator water supply can having a spout and a shield to partially close the open end of said can, a plate to receive a placard, means on said plate bendable to engage and hold said placard on said plate and means integral with said plate bendable about the edge of said shield to hold said plate to position the placard within the range of vision of the occupants of an automobile when the end of said spout is positioned to discharge wa-

ter into the inlet of an automobile radiator.

In testimony whereof, I have hereunto subscribed my name this 19th day of August, 1930.
